UNITED STATES PATENT OFFICE.

BARTHOLOMEW R. DOODY, OF CANTON, MASSACHUSETTS.

LOW-PRESSURE STEAM AND ANALOGOUS HEATING SYSTEM.

No. 911,215.

Specification of Letters Patent.

Patented Feb. 2, 1909.

Application filed January 24, 1908. Serial No. 412,395.

To all whom it may concern:

Be it known that I, BARTHOLOMEW R. DOODY, a citizen of the United States, residing at Canton, in the county of Norfolk and 5 State of Massachusetts, have invented certain new and useful Improvements in Low-Pressure Steam and Analogous Heating Systems, of which the following is a specification.

10 My invention pertains to low pressure steam and analogous heating systems; and it has for one of its objects to provide an apparatus comprising means for automatically closing a furnace-door or damper when the 15 pressure in the boiler of the system attains a predetermined point and for opening the said door or damper when the pressure is reduced below the undue point, this with a view of assuring the maintenance of a uniform pressure 20 and the furnishing of a uniform degree of heat.

Another object of the invention is the provision of simple and reliable means for indicating to interested parties the amount of 25 pressure present in the boiler of the system.

Another and very important object is the provision of means for permitting the escape 30 of steam and relieving the system from high pressure and the danger consequent thereupon in the event of the furnace-door or 35 damper failing for any reason to open when the working pressure in the system is raised to the predetermined high point.

The nature and the novelty, utility and 40 practical advantages of the invention will be fully understood from the following description and claims when the same are read in connection with the drawings, accompanying and forming part of this specification, in

45 Figure 1 is a view partly in elevation and partly in vertical section, illustrating the apparatus constituting the best practical embodiment of my invention of which I am aware; Fig. 2, a detail elevation showing the 50 adjustable connection of the furnace-door or damper cable to the float; and Fig. 3, a detail section taken in the plane indicated by the line 3—3 of Fig. 1 and showing the connection between the lower ends of the 55 duplex water gages and the water-container of the apparatus.

Similar letters designate corresponding parts in all of the views of the drawings, referring to which:

A is the expansion tank of the apparatus

which is preferably in the form of an upright cylinder. The upper end of the said tank is open to the atmosphere, and with the lower end or portion thereof is connected a conduit 60 B leading from the boiler (not shown) of the system. In the expansion tank and movable up and down on the body of water therein contained is a suitable float C and to the said float is connected, preferably in the adjustable manner best shown in Fig. 2, a cable D in the form of a chain which is designed, in turn, to be connected with a furnace-door or damper (also not shown). Thus it will be manifest that when the working pressure in the system reaches a predetermined high point, the pressure in the conduit B and the expansion of the heated water raises the water in the expansion tank and lifts the float and through the float and cable closes the furnace-door or 70 damper and checks the fire. Then when the checked fire results in a reduction of pressure in the boiler, the descending water and float in the expansion tank effect through the cable D a reopening of the furnace-door or damper, 75 and consequently a uniform pressure is maintained in the system and the same is enabled to give off a uniform degree of heat.

With a view of enabling interested persons to note at a glance the amount of pressure 85 present in the system, the duplex water gages E and F are provided. These gages are arranged outside of the expansion tank A and their lower ends are connected through a valved connection G, Figs. 1 and 3, with the 90 body of water contained in the tank. One of the said gages, namely the gage E, is open at its upper end to the atmosphere, while the other gage F is connected, preferably through a valved pipe H with a pressure pipe I forming part of the systems. From this it follows that the gage F interposed between the tank A below the water line and the pressure pipe I will show the height of the water in the boiler of the system, and the other gage E 95 open at its upper end to the atmosphere will because of the pressure present in the system show a higher level of water, while the difference between the heights of the water in the two gages will indicate the amount of pressure 100 in the boiler system.

The pressure pipe I extends down into a water seal contained in a sub-tank J disposed at one side of the expansion tank A, and from the said pipe I, at about the proportional distance illustrated above the lower end thereof, leads a vent pipe K which ex-

tends upward and terminates in a goose-neck M. This provision is made for the sake of safety for it will be evident that in the event of the furnace-door or damper failing for any reason to work, and the pressure in the system rising to a dangerous point, the excess pressure will force the water down pipe I to a point below where pipe K joins the pipe I, whereupon the steam will escape through the pipe K to the atmosphere until the pressure in the system is reduced to the normal. It will also be noted in this connection that any water that may be carried upward by the escaping steam will by the goose-neck M be returned to the sub-tank J, the upper end of which is preferably open. An overflow aperture N is provided for the sub-tank J, through which any excess of water will overflow into the expansion tank A.

20 The furnace-door or damper hereinbefore referred to may by adjustment of the float C on cable D be arranged to close at any desired or proper pressure in the discretion of the party installing the apparatus.

25 In addition to the practical advantages hereinbefore ascribed to my novel apparatus it will be noted that the apparatus is simple and inexpensive in construction and is calculated to withstand for an indefinite period the usage to which apparatus of corresponding character is ordinarily subjected.

As before stated the construction herein shown and described constitutes the best embodiment of my invention of which I am cognizant, but I would have it understood that I do not restrict myself to the particular construction and relative arrangement of parts shown as such changes may be made in the same as do not depart from the spirit of my invention or the scope thereof as defined in the claims appended.

Having described my invention, what I claim and desire to secure by Letters Patent is:

45 1. The combination of a water-holding tank provided with a water-connection which communicates freely with the water chamber of a boiler; a damper-controlling float carried by the water in said tank; a pair of juxtaposed gages the lower end of each of which communicates freely with the lower part of said tank and the upper end of one of which is open to atmospheric pressure; and a steam pipe which leads live steam at boiler pressure into the upper end of the other of said gages, the difference in level of the water in said gages measuring the said boiler pressure.

60 2. The combination of a water-holding tank provided with a water-connection which communicates freely with the water chamber of a boiler; a pair of juxtaposed gages the lower end of each of which communicates freely with the lower part of said tank and the upper end of one of which is open to atmospheric pressure; damper-controlling

means mounted in said tank, and controlled in position by the pressure in said tank; and a steam pipe which leads live steam at the boiler pressure into the upper end of the other of said gages, the difference in level of the water in said gages measuring the said boiler pressure. 70

3. The combination of a water-holding tank provided with a water-connection which communicates freely with the water-chamber of a boiler; a damper-controlling float carried by the water in said tank; a water-seal tank; a steam-pipe which leads from the steam-chamber of the boiler and extends into the water in said water-seal 75 tank; and a vent-pipe connected with said steam-pipe below the level of the water in said water-seal tank; said vent-pipe carrying away live steam and reducing the boiler pressure in case said damper-controlling float fails to maintain the boiler pressure below a certain predetermined limit or maximum. 85

4. In an apparatus for the purpose described, an expansion tank adapted to contain water and having an upper portion 90 open to the atmosphere and a lower portion adapted to be connected with a boiler, a sub-tank arranged alongside the expansion tank and adapted to hold a water seal, a pressure pipe extending down in the seal and open at its lower end, and a vent pipe leading upward from an intermediate point of the portion of the pressure pipe in the seal to a point above the seal where it communicates with the atmosphere. 95

5. In an apparatus for the purpose described, an expansion tank adapted to contain water and having an upper portion open to the atmosphere and a lower portion adapted to be connected with a boiler, a 105 sub-tank arranged alongside the expansion tank and adapted to hold a water seal, a pressure pipe extending down in the seal and open at its lower end, a vent pipe leading upward from an intermediate point of the portion of the pressure pipe in the seal to a point above the seal where it communicates with the atmosphere, and a float 110 movable in the expansion tank and adapted to be connected with a furnace damper or 115 the like.

6. In an apparatus for the purpose described, an expansion tank adapted to contain water and having an upper portion open to the atmosphere and a lower portion 120 adapted to be connected with a boiler, a sub-tank arranged alongside the expansion tank and adapted to hold a water seal, a pressure pipe extending down in the seal and open at its lower end, a vent pipe leading 125 upward from an intermediate point of the portion of the pressure pipe in the seal to a point above the seal where it communicates with the atmosphere, a water gage connecting the lower portion of the expansion 130

tank and the pressure pipe, and a second water gage arranged adjacent to the first mentioned gage and connected at its lower end to the expansion tank and having its 5 upper portion open to the atmosphere.

7. In an apparatus for the purpose described, an expansion tank adapted to contain water and having an upper portion open to the atmosphere and a lower portion 10 adapted to be connected with a boiler, a sub-tank arranged alongside the expansion tank and adapted to hold a water seal, a pressure pipe extending down in the seal and open at its lower end, a vent pipe leading upward from an intermediate point of the 15 portion of the pressure pipe in the seal to a

point above the seal where it communicates with the atmosphere, a float movable in the expansion tank and adapted to be connected with a furnace damper or the like, a water 20 gage connecting the lower portion of the expansion tank and the pressure pipe, and a second water gage arranged adjacent to the first mentioned gage and connected at its lower end to the expansion tank and having 25 its upper portion open to the atmosphere.

In testimony whereof I hereunto affix my signature in the presence of two witnesses.

BARTHOLOMEW R. DOODY.
